PORTABLE DRILLING RIG

Charles A. Hirschberg, Mountain Lakes, N. J.,
assignor to Worthington Pump and Machinery
Corporation, New York, N. Y., a corporation
of Virginia

Application August 18, 1934, Serial No. 740,380

9 Claims. (Cl. 255—51)

This invention relates to portable drilling rigs and more particularly to supporting rigs for percussive tools of such type as are commonly known as wagon drills.

An object of the present invention is to provide a drilling rig or wagon drill which is simple in construction, relatively light in weight and when equipped with a pneumatic or percussive tool may be moved from place to place by one man and which is so constructed that many different adjusted positions of the tool may be had, for various types and kinds of drilling operations. More specifically, an object of the invention is to provide a one-man wagon drill rig for use in various types of drilling with pneumatic drills of the hammer piston type.

With these and other objects in view, as may appear from the accompanying specification, the invention consists of various features of construction and combination of parts, which will be first described in connection with the accompanying drawings, showing a portable drilling rig of the preferred form, and the features forming the invention will be specifically pointed out in the claims.

In the drawings:

Fig. 1 is a front elevation of the improved drilling rig.

Fig. 2 is a side elevation of the drilling rig.

Fig. 3 is a top plan of the improved drilling rig.

Fig. 4 is a section on the line 4—4 of Fig. 3.

Figures 5 to 13 inclusive are views in side elevation, front elevation and top plan showing various positions and adjustments of the improved drilling rig, for drilling various types of holes.

Referring more particularly to the drawings, the improved one-man portable drilling rig comprises a substantially U-shaped chassis 1 which has axial spindles 2 securely attached in any suitable manner such as by detachable brackets 3 to the legs of the chassis 1 adjacent to their ends as clearly shown in Fig. 3 of the drawings. A suitable cross-brace 4 is provided intermediate the ends of the legs of the chassis 1 and the cross-bar 5 or loop 5 thereof. A handle 6 is connected to the cross-bar or loop 5 of the chassis to facilitate the movement of the rig from one place to another by a man. Anchoring pins 7 are adjustably carried by the chassis 1 adjacent to the loop or cross-bar 5 and they are clamped in adjusted positions by the tightening of the nuts 8 on the threaded stems 9 of the anchor-bar carrying members 10. The tightening of the nuts 8 on the threaded stems 9 clamp the anchor bars 7 against the sta-

tionary members 11 which are secured to the chassis 1.

Intermediate the ends of the legs of the chassis 1 are located a pair of bearing structures 12 which are disposed directly opposite to each other and comprise the sections 13 which are attached to the chassis, and the caps 14 which are attached to the sections 13 by means of the bolts 15 and nuts 16. The bearings 12 receive the spindle ends 17 of the substantially U-shaped tool-carrying frame 18. The tool-carrying frame 18 has a bracket 19 adjustably mounted upon the cross-bar 20 thereof so that a percussive tool (not shown) carried by the bracket 19 may be adjusted in the same horizontal plane laterally along the cross-bar 20 for the purpose of drilling a series of holes alongside of each other. The frame 18 is, of course, through the medium of the bearings 12, pivotally supported by the chassis 1 and it may be moved into any desired position or angle 20 with respect to the horizontal to vary the elevation of the drill or pneumatic tool carried by the bracket 19 for drilling horizontal holes at various elevations or at various angles with respect to the horizontal or the perpendicular. Also, by 25 the particular construction of the drill rig, the frame 18 may be lowered sufficiently that holes may be drilled horizontally or at slight angles to the horizontal in planes below the plane of the axis of the axial spindles 2.

The various Figures 5 to 13 illustrate positions and adjustments of the substantially U-shaped drill carrying frame 18 showing the flexibility of adjustment of the drilling rig for various types of drilling.

Figure 5 shows the U-shaped supporting frame 18 positioned perpendicularly with respect to the horizontal carrying frame 1 with the drill indicated at A positioned vertically for down hole drilling.

Figure 6 is a front elevation of the drilling rig adjusted as shown in Figure 5 and the dot-and-dash lines B indicate lateral angles at which the drill A may be adjusted for drilling a plurality of holes from a single setting of the drill rig.

In Figure 7 the substantially U-shaped carrying frame 18 is shown as tilted to the rear from the supporting wheels of the drill rig with the drill A positioned vertically for down hole drilling.

Figures 8 and 9 show a side elevation and a front elevation respectively of the portable drilling rig adjusted to permit line drilling. In this type of drilling the supporting frame 18 is tilted forwardly so that the drill holes will be drilled 55

- forwardly of the wheels of the rig. For line drilling the drill A is moved longitudinally along the cross bar 20 of the frame 18 as indicated by the dot-and-dash lines C.
5. In Figures 10 and 11 the drill carrying frame is shown as adjusted for breast drilling and while in these figures the frame 18 is shown perpendicular, to position the drill A at the highest elevation above the horizontally supporting frame 1 it is to be understood that by tilting the frame 18 at various angles the distance of the drill holes above the frame 1 may be varied or regulated as desired. One of such positions is shown in dotted lines in Figure 10 of the drawings, while various 15 angular positions of the drill, horizontally is indicated by the dot-and-dash lines D in Figure 11.

Figures 12 and 13 illustrate adjustment of the drilling rig for snake holing. In Figure 12 the frame 18 and the drill A are shown in adjusted 20 positions to permit snake holing or side hill drilling at positions above the frame 1 and the axis of the supporting wheels of the drill rig.

In Figure 13 the frame 18 and the drill A are shown as adjusted to permit snake hole drilling 25 below the plane of the frame 1 and below the axis of the supporting wheels of the drill rig.

These various figures of the drawings illustrate some of the many different positions into which the frame 18 and the drill A carried thereby may 30 be adjusted to provide for practically any type or condition of drilling which may be met in practically any project where a light portable drilling rig is applicable for use.

It will be understood that the invention is not 35 to be limited to the specific construction or arrangement of parts shown but that they may be widely modified within the invention defined by the claims.

What is claimed is:

- 40 1. In a portable drilling rig, the combination, of a chassis, wheels at one end of the chassis, a handle at the other end of the chassis, clamping bearings carried by said chassis, a substantially U-shaped tool-supporting frame, spindles 45 on said frame engaging in said bearings for connecting the frame to the chassis to permit pivotal movement in an arc of approximately 180° of the frame about a horizontal axis means cooperating with said bearings for holding said frame in 50 adjusted positions, a tool-supporting bracket adjustably carried by the cross-bar of said U-shaped supporting frame, and anchoring pins adjustably carried by said chassis adjacent to said handle.
2. In a portable drilling rig, the combination, 55 of a chassis, wheels at one end of the chassis, clamping bearings carried by the chassis, a substantially U-shaped tool-supporting frame, spindles on said frame engaging in said bearings for connecting the frame to the chassis to permit 60 pivotal movement of the frame about a horizontal axis, and a tool supporting bracket adjustably carried by the cross bar of said U-shaped supporting frame.
3. In a portable drilling rig, the combination, 65 of a chassis, wheels at one end of the chassis, clamping bearings carried by said chassis, a substantially U-shaped tool-supporting frame, spindles on said frame engaging in said bearings for connecting the frame to the chassis to permit 70 pivotal movement of the frame about a horizontal axis, a rock drilling mechanism, means pivotally and adjustably connecting said rock drilling mechanism intermediate its ends to the portion of the U-shaped supporting frame which is parallel to its pivotal axis, whereby the drilling

mechanism is adjustable longitudinally of the drilling rig by pivotal movement of the U-shaped supporting frame and is pivotally adjustable on an axis transversely of the axis of the U-shaped supporting frame.

4. In a portable drilling rig, the combination, of a chassis, wheels at one end of the chassis, clamping bearings carried by the chassis, a substantially U-shaped tool-supporting frame, spindles on said frame engaging in said bearings for connecting the frame to the chassis to permit pivotal movement of the frame about a horizontal axis, and a tool supporting bracket adjustably carried by the cross bar of said U-shaped supporting frame, said bracket constructed and arranged to permit pivotal movement of a rock-drilling mechanism carried thereby about axes parallel to and transversely of the pivotal axis of the U-shaped supporting frame.

5. In a portable drilling rig, the combination, 20 of a chassis, wheels at one end of the chassis, clamping bearings carried by the chassis, a substantially U-shaped tool-supporting frame, spindles on said frame engaging in said bearings for connecting the frame to the chassis to permit 25 pivotal movement of the frame about a horizontal axis, a tool supporting bracket adjustably carried by the cross bar of said U-shaped supporting frame, said bracket adjustable along the portion of said U-shaped frame parallel to its 30 pivotal axis, said bracket constructed and arranged to permit pivotal movement of a tool carried thereby about axes parallel to and transversely of the pivotal axis of the U-shaped supporting frame.

6. In a portable drilling rig, the combination, of a chassis, wheels at one end of the chassis, clamping bearings carried by the chassis, a substantially U-shaped tool-supporting frame, spindles on said frame engaging in said bearings for 40 connecting the frame to the chassis to permit pivotal movement of the frame about a horizontal axis, and a tool supporting bracket adjustably carried by the cross bar of said U-shaped supporting frame, and means cooperating with 45 said bearings for holding said tool-supporting frame in adjusted positions.

7. In a portable drilling rig, the combination, of a chassis, wheels at one end of the chassis, clamping bearings carried by the chassis, a substantially U-shaped tool-supporting frame, spindles on said frame engaging in said bearings for connecting the frame to the chassis to permit 50 pivotal movement of the frame about a horizontal axis, a tool supporting bracket adjustably carried by the cross bar of said U-shaped supporting frame, said bracket adjustable along the portion of said U-shaped frame parallel to its 55 pivotal axis, said bracket constructed and arranged to permit pivotal movement of a tool carried thereby about axes parallel to and transversely of the pivotal axis of the U-shaped supporting frame, and means cooperating with said bearings for holding said tool-supporting frame in 60 adjusted positions.

8. In a portable drilling rig, the combination of a chassis having one end open, wheels on the chassis at said open end, a substantially U-shaped tool-supporting frame, bearings for said supporting frame carried by said chassis inwardly of said open end and having their axes in a horizontal plane spaced from the horizontal plane of the axes of said wheels, spindles on said U-shaped frame and engaging said bearings for pivotally connecting the U-shaped frame to the 70 75

chassis whereby the U-shaped frame may be swung across the plane of the carrying frame without overbalancing the drilling rig.

9. In a portable drilling rig, the combination, of a chassis, wheels at one end of the chassis, a substantially U-shaped tool-supporting frame, means for pivotally connecting said U-shaped frame to said chassis including bearings, means forming a part of said bearings for holding said 10 U-shaped frame in adjusted positions, a tool sup-

porting bracket adjustably carried by the cross-bar of said U-shaped supporting frame, a rock drilling mechanism carried by said bracket, said bracket constructed and arranged to permit pivotal movement of the rock drilling mechanism 5 carried thereby about axes parallel to and transversely of the pivotal axis of the U-shaped supporting frame.

CHARLES A. HIRSCHBERG. 10
